United States Patent Office

Des. 204,530
Patented Apr. 19, 1966

204,530

HEAT EXCHANGER UNIT

Harold J. Loehlein, Henrico County, Va., and Edward E. Curran, Louisville, Ky., assignors to Reynolds Metals Company, Richmond, Va., a corporation of Delaware

Filed Nov. 16, 1964, Ser. No. 82,607

Term of patent 14 years

(Cl. D81—21)

FIG-1

FIG-3

FIG-4

FIG-5

FIG-2

FIGURE 1 is a perspective view of the heat exchanger unit of this invention;

FIGURE 2 is a front view of the heat exchanger unit of FIGURE 1;

FIGURE 3 is a side view of the heat exchanger unit of FIGURE 1;

FIGURE 4 is an enlarged, fragmentary, perspective view of part of the tubular member of the heat exchanger unit of FIGURE 1; and

FIGURE 5 is a cross-sectional view taken on line 5—5 of FIGURE 4.

We claim:

The ornamental design for a heat exchanger unit as shown.
